ABSTRACT

A stand for periodicals with a frame and trays attached to the frame for receiving periodicals. The frame is usually an upright post. Each periodical tray has a lateral flange that is secured to one side of the post. The flange is so shaped that when it is secured to the post the periodical tray extends downwardly and away from the post at an acute angle.

5 Claims, 3 Drawing Figures

FIG. 1

FIG. 2

FIG. 3

1
DISPLAY STAND

The invention relates to a stand for periodicals of the type useful in libraries, etc.

According to the invention, a stand for periodicals comprises a frame and a plurality of trays, each to receive a periodical, the frame comprising at least one upright post, each periodical tray having a lateral flange securable to one side of the upright post and so shaped that when secured to the upright the tray extends downwardly away from the upright at an acute angle.

Preferably, the lateral flange is of generally trapezoidal shape.

The upright post may be mounted on a wall or the frame may comprise a base having a number of uprights spaced apart along one axis of the base, the posts being mounted on the base so that they have a side portion for receiving the lateral flange of the trays located at one angle with respect to the axis.

Preferably, the frame and the trays are made of metal, such as steel.

An embodiment of the invention is illustrated by the accompanying drawings in which:

FIG. 1 is a plan view of one form of stand frame showing some trays in ghost outline;

FIG. 2 is a side elevation of one periodical tray;

FIG. 3 is an end view of the frame of FIG. 1 to which are secured two trays of FIG. 2.

The frame of FIG. 1 comprises a base part 2 on which are mounted upright posts 3. The base part 2 is generally H-shaped in plan view and may have wheels or runners (not shown) so that the frame can be moved from place to place. The posts 3 are arranged in spaced apart relation in a line along the bridge arm of the H-shaped base part 2. Each post 3 is generally square in cross-section and is so mounted that each of the side portions 4 lies at an angle of about 45° with respect to the adjacent side of the base. One of the side portions 4-A has pairs of vertically spaced apart screw receiving holes 5, as best shown in FIG. 3. The posts 3 and the base part 2 are preferably both made of steel and conveniently the posts are welded onto the base part.

Each periodical tray 6 shown in FIGS. 2 and 3 comprises a back flange 7 having at a lower end an upturned lip 8. The tray has one depending lateral flange 9 which is of generally trapezoidal shape. A pair of screw receiving holes 10 is located adjacent the edge of the flange 9 remote from the back flange 7.

In use, a tray 6 is abutted against an upright post 3 so that the screw holes 11 of the flange 9 are aligned with a pair of screw holes 5 in the post side portion 5-a. Screws are then fitted in to hold the tray 6 to the post 3. Because of the shape of the flange 9 the back flange 7 of the tray extends downwardly and the lip 8 is lo-

2

cated to prevent a periodical from falling off the tray. A plurality of such trays may be located on each post of the frame to form a multi-tray stand. Because of the location of each tray on the frame, the periodicals are each easily accessible and prominently displayed.

Although the embodiment shows a plurality of upright posts on one base part, the latter may have only one post. Also, the trays may be mounted on more than one side portion of the upright posts in vertically staggered relation. In addition, the base part may be omitted and the upright posts may be mountable on a wall, for example, by arranging each upright to be of generally triangular shape in plan, the base of the triangle being securable to the wall and the trays being mountable on either side of the triangle.

The invention includes, for use with the stand, a periodical tray, as defined.

Without further elaboration, the foregoing will so fully illustrate my invention, that others may, by applying current or future knowledge, readily adapt the same for use under various conditions of service.

What is claimed as the invention is:

1. A stand for periodicals comprising a frame supporting a plurality of trays, each of said trays being arranged to directly support a periodical thereon, said frame comprising at least one upright post, each periodical tray comprising a lateral flange including a front edge and a rear edge, said front edge extending at an angle to said rear edge, and a planar body portion having a side edge and a lower edge, with a lip projecting from said lower edge, said planar body being of sufficient width to directly support a periodical, the front edge of said lateral flange being connected to said planar portion at said side edge with said flange being disposed normally to said planar portion, said flange being secured to one side of the upright post with the portion of the flange adjacent the back edge being abutted against said side, whereupon the planar body of the tray extends downwardly away from the upright at an acute angle thereto.

2. A stand according to claim 1 in which the lateral flange of the periodical tray is of generally trapezoidal shape.

3. A stand according to claim 1 in which the frame comprises a number of uprights spaced apart along one axis of the base, with the posts being mounted on the base so that they each have a side portion for receiving the lateral flange of the trays located at an angle with respect to the axis.

4. A stand according to claim 1 in which each upright post is adapted to be mounted on a wall.

5. A stand according to claim 1 in which the frame and the trays are made of metal, such as steel.
